COMBINED PHOTOMOUNT AND FRAME

Edward G. Beikirch, Rochester, N. Y.

Application May 26, 1942, Serial No. 444,601

6 Claims. (Cl. 40—154)

This invention relates to photomounts and has for its principal object to provide a novel construction for a photomount in which a member thereof is combined with a hollow frame as an integral part thereof so as to surround the mask portion of the photomount, and another member of the photomount serves to hold the frame extended.

Another object of this invention is to provide a combined photomount and frame in which the hollow frame is formed from an integral portion of the mask, and the insert functions to hold the hollow frame extended.

A further object of this invention is to provide a combined photomount and frame in which the hollow frame is formed from an integral portion of the insert, and the mask serves to hold the hollow frame extended.

These and other objects of this invention will become more readily apparent from the detailed description thereof which follows, reference being had to the accompanying drawings in which

Figure 1 is a perspective view of my novel combined photomount and frame.

Figure 2 is a side elevation thereof.

Figure 3 is a horizontal sectional view taken on the line 3—3 in Figure 1.

Figure 4 is a vertical section taken on the line 4—4 in Figure 1.

Figure 5 is a front elevation of a modified form of the combined photomount and frame.

Figure 6 is a horizontal section taken on the line 6—6 of Figure 5.

Figure 7 is a detail plan view of the corner of the blank from which the mask of the combined photomount is formed.

Figure 8 is a front elevation of the corner of the mask formed up from the blank.

Figure 9 is a sectional view of the corner taken on the line 9—9 in Figure 8.

The novel photomount construction forming the subject matter of my present invention is especially useful at the present time in that it eliminates the need for metal or plastics in the construction of frames for the display of the photomount and its picture. Photomounts have heretofore been embossed to simulate a frame by surface ornamentation. However in my present invention the photomount embodies a frame not only in appearance but also in construction. The frame portion of the mount is furthermore made from the same stock as that of one of the members of the photomount so that both the member and the frame may be made from a single piece of sheet stock. As the sheet stock from

which the member and frame is made may be of comparatively thin sheet stock, my novel construction provides for the reinforcement of the frame portion of the photomount.

In the construction illustrated in Figures 1 to 5 of the drawings, the combined photomount and frame comprises the mask 1 which has its edge portion bent forwardly at 2, thence rearwardly at 3 and thence inwardly at 4. A hollow frame is thus formed on the edge of the mask which may be triangular in cross section as illustrated in Figures 1, 3 and 4 or which, by modification, may have other cross sections without departing from the scope of the invention. The insert 5 is placed behind the mask 1 so that its edge extends to the side 3 of the hollow frame to hold it uniformly and rigidly expanded. The inwardly extending edge portion 4 of the mask overlaps the back of the insert 5 and is suitably cemented to it to add its thickness to that of the insert for the purpose of spacing the back 6 from the mask 1. The back is suitably cemented to the inwardly extending edge portion 4 of the mask and a suitable collapsible easel 7 is in turn attached to the back 6 so that the combined photomount and frame may be readily supported on any flat surface. Inserts have heretofore had the sole function of providing the necessary space for the picture receptacle for the mount and for this reason its thickness had to provide a space sufficient for the insertion of the picture proper. In my present invention the thickness of the insert 5 is supplemented by the thickness of the inwardly extending edge portion 4 of the mask so that the thickness of the insert may be correspondingly reduced and still provide the same depth for the picture receptacle.

In order to firmly hold the picture in the picture receptacle against the back of the mask 1, a pad 9 in the form of a sheet member is attached to the back 6 so as to project into the picture receptacle provided between the mask and the back. This pad has substantially the same outline as the opening in the mask to have it exert its pressure against the picture within the opening of the mask and hold the picture flat within the opening of the mask.

The insertion of the picture into the picture receptacle formed behind the mask is made possible by the slit 8 in the back 6 which extends across the top of the receptacle so that the portion of the back below the slit may be slightly forced rearwardly as illustrated in dotted lines in Figure 4 to permit the ready insertion of a

picture into the picture receptacle of the photomount thru the back thereof.

In order to simulate a metal frame or a frame of any other material, the frame portion of the photomount may be suitably coated with a metallic paint or other surface coating and ornamentation.

In the modification of my novel combined photomount and frame construction illustrated in Figures 5 and 6 of the drawings, the frame portion of the photomount is provided as an integral edge portion of the insert 11 instead of an integral portion of the mask 1 as is the case in the structure illustrated in Figures 1 to 4. The edge portion of the modified insert 11 is bent forwardly at 12 and then inwardly and rearwardly at 13 against a separate mask 10. The hollow frame is thus formed by the edge portion of the insert and is held extended by the edge portion of a separate mask which abuts against the outwardly bent portion of the frame. The separate mask 10 is suitably fastened to the front of the insert 11 and the back 14 is suitably fastened to the rear of the insert to have the insert space the separate mask from the back and provide the picture receptacle between them within the opening of the insert. A pad 9, such as is illustrated in connection with the combined photomount and frame construction illustrated in Figures 1, 3 and 4, may also be attached to the back 14 of the photomount and frame illustrated in Figures 5 and 6.

It is important in this type of hollow frame when folded up from paper sheet stock that the joints between the folded corner sections be made substantially invisible. The blank for the corner sections of the frame are cut as illustrated in Figure 7 in which the corners are cut away at 12 and 13 to permit the folding of the rearwardly and inwardly extending edge portions 3 and 4 of the frame. The joint in the outwardly extending edge portion 2 is made possible by the V shaped slit 15 which extends inwardly of the cut away blank as illustrated in Figure 7. One side of this V shaped slit is formed by the small V shaped flange 15A which is partially severed from the blank to provide for easy folding when pressure is brought against it. On the folding of the corner portion of the hollow frame, this V shaped flange is automatically bent inwardly when the opposing edge provided by the V slot is forced against it on the formation of the frame as illustrated in Figure 9. The widened edge of the blank thus provided by the flange 15A forms an enlarged bearing surface against which the opposing edge rests in order to keep both edges of the abutting edge portions 2 from overlapping when brought against each other. The angular joint 16 between the edge portions 2 at the corners of the frame is thus held in perfect alignment and made practically invisible.

I claim:

1. A combined photo mount and frame including a mask member and an insert member with a large opening in one of said members and a

smaller opening in the other of said members, said members being arranged to have the smaller opening located in front of the larger opening, one of said members having an integral edge portion bent around the edge portion of the other member to form a hollow frame around said second named member, and a back attached to one of said members on the back thereof to close the larger of said openings and provide a picture receptacle in register with the smaller of said openings.

2. A combined photo mount and frame including a mask member and an insert member with a large opening in one of said members and a small opening in the other of said members arranged to have the member with the small opening overlap the member with the large opening, one of said members having an integral edge portion bent around the edge portion of the other member to form a hollow frame around said second named member, a back attached to the back of one of said members to provide a picture receptacle in the large opening between said back and the member with the small opening, and a pad on said back held centrally in the large opening spacedly from the plane of the small opening.

3. A combined photomount and photoframe comprising a mask having an edge portion bent forwardly, thence rearwardly and thence inwardly thereof to form a hollow frame around said mask, an insert between said mask and its inwardly extending edge portion to hold said hollow frame extended, a back member fastened against the inwardly extending edge portion of said mask to provide a picture receptacle between said back member and said mask within said insert by spacedly holding said back member from the rear of said mask by means of said insert and said inwardly extending edge portion of said mask.

4. A combined photomount and photoframe as set forth in claim 3 in which said back member is provided with an opening within said picture receptacle to provide for the insertion of a picture thru said back member into said picture receptacle.

5. A combined photomount and photoframe comprising a mask having an opening therethru, an insert having an edge portion bent forwardly and inwardly against said mask to form a hollow frame around said mask with the edge of said mask abutting the sides of said hollow frame to hold said frame extended, said insert having an opening therethru in register with the opening in said mask, and a back member attached to said insert to provide a picture receptacle between said mask and said back within the opening of said insert.

6. A hollow frame folded from a single piece of sheet stock, abutting edge portions at the corners of the frame, and a flange bent substantially at right angles to the abutting edges on one of said abutting edge portions of the frame.
